HEAD FOR A STEEL GUITAR

Kenneth V. Paul, 824 S. Jackson St., Waukegan, Ill.

Filed June 3, 1964, Ser. No. 80,272

Term of patent 14 years

(Cl. D56—1)

FIGURE 1 is a top plan view of a head for a steel guitar, showing my new design;

FIGURE 2 is a side elevational view thereof; and

FIGURE 3 is an end elevational view thereof.

The characteristic feature of my design resides in a head for a steel guitar, having a stepped internal opening, with the massiveness of the head changing by steps from one end to the other end of the head.

I claim:

The ornamental design for a head for a steel guitar, substantially as shown and described.
